ELECTRICAL SOCKET

Louis W. Cole, New York, and Christopher I. Smith, Sunnyside, Long Island, N. Y., assignors to Cole Electric Products Co., Inc., Long Island City, N. Y., a corporation of New York

Application January 6, 1938, Serial No. 183,580

5 Claims. (Cl. 173—358)

This invention relates to electrical sockets for plug fuses, lamps, and other electrical connecting or translating devices.

In the socket embodying the present invention provision is made for connecting a wire or other conductor to the socket shell externally thereof and for securing said wire in position, in electrical connection with the shell bottom in such manner that it is unnecessary to bend the wire.

10 One of the objects of the invention is to provide means for facilitating the electrical connection and mechanical securement of the wire to the bottom of the shell in this manner.

Another object of the invention is to provide 15 a socket of the class described which is simple in construction and which has parts which are capable of being readily and conveniently assembled.

A yet further object of the invention is generally to improve the construction of sockets of the class described whereby to simplify said construction, to facilitate the assembly of the several parts of the socket, and also to facilitate the attachment of the wire to the socket shell.

25 The above objects of the invention and other objects which might hereinafter appear will be fully understood from the following description considered with reference to the accompanying drawing.

30 In the drawing:

Fig. 1 is a plan view of the socket made in accordance with one form of the present invention;

Fig. 2 is a sectional view on the line 2—2 of Fig. 1;

35 Fig. 3 is a sectional view on the line 3—3 of Fig. 2;

Fig. 4 is a perspective view showing, in separated relation, a socket shell and parts associated therewith;

40 Fig. 5 is a view similar to Fig. 2 showing another form of the invention;

Fig. 6 is a sectional view on the line 6—6 of Fig. 5.

45 Referring now to the drawing in greater detail, the socket 10 comprises, as here shown, a housing 12 which is composed of any suitable insulation material and which is provided with an open-top recess 14 in which is seated a metal socket shell 16 which, as here shown, is of the screw shell type to receive the threaded part of a connecting or translating device, such as the threaded base of the lamp or plug fuse.

50 The bottom 18 of screw shell 16 is seated on the bottom 20 of recess 14 of housing 12, which 55 is provided with a longitudinal passage 24. The

center contact 26 of the shell has a slotted head 28 in position adjacent the shell bottom 18, and a screw threaded shank 30 which extends from inside the shell through opening 22 and into passage 24 for securement with the conducting 5 member 32 positioned in a lateral recess 34 in the bottom of housing 12. Said recess 34 extends from a point adjacent passage 24 to one side of the housing. Center contact 26 is insulated from shell bottom 18 by a semi-circular insulation 10 disc 36, the shank 30 of said center contact member passing through the opening 38 in the disc and threaded into conducting member 32.

An important feature of the present invention resides in the provision of means for facilitating 15 the electrical connection and mechanical securement of a wire to the bottom 18 of the shell externally thereof and in such manner as to obviate any necessity for the bending or other substantial deformation of the wire. For this 20 purpose housing 12 is provided with a lateral passage 40 which extends from one side of the housing in the bottom portion thereof below the shell bottom 18 and below the bottom 20 of recess 14. Socket shell 16 has an opening 42 25 in its bottom 18 offset laterally from opening 22 adjacent the inner end of passage 40 and adjacent the side wall of the shell, opening 44 being formed in said side wall of the shell as a continuation of opening 42. A metal clamping member 45 is positioned below the shell bottom 18 30 adjacent opening 42 therein and is provided with a clamping portion 46 arranged to engage the bare end 48 of a wire 50 which is inserted in and extends into passage 40 in juxtaposition to shell bottom 18 for engagement by clamping member 45 to hold the same firmly in electrical connection with and in mechanical securement 35 in relation to shell bottom 18. The clamping portion 46 is upturned and terminates in a straight end portion 52 which is positioned in shell opening 22 close to or in engagement with the straight edge 54 of said opening. It will be observed that the straight edge 55 of insulation disc 36 is spaced from the edge 54 of opening 22 a distance only slightly larger than the thickness of edge portion 52 of clamp member 54. It will be observed also that the width of said edge 54 of opening 22 is only slightly greater than the width of edge 52 of the clamping member 45. Clamping member 45 is releasably secured and adjusted by a clamping screw 56 having a slotted head 58 and a threaded shank 60, head 58 having an enlarged flanged portion 62 which engages shell bottom 18 internally there-

40
45
50
55

of and shank 60 being threaded into an opening 63 in clamping member 45. It will be understood that the engagement of edge portion 52 of clamping member 45 in opening 22 adjacent edge 54 of the bottom of the shell at said opening opposes outward movement of said clamping member through the lateral opening in the side of the shell when said clamping member is in wire-clamping relation, and it will be further understood that the position of said part 52 of clamping member 45 in said opening 54 prevents turning movement of the clamping member when the adjusting screw is turned for clamping and releasing the wire.

15 It will be understood that wire 50 is readily connected to the bottom 18 of socket shell 16 by inserting said wire through passage 40 so that the bare end 48 of the wire is positioned between the bottom of the shell and the portion 46 of clamping member 45 and so that by tightening adjusting screw 56 said bare end of the wire is securely clamped by member 45 in position against the shell bottom. An opening 66 through the shell bottom 18 permits observation of the 25 end 48 of the wire whereby the proper position of said wire, when connected to the bottom of the shell, may be readily ascertained, viewing the interior of the shell.

In the form of the invention illustrated in 30 Figs. 5 and 6 the socket, including the housing 12 and the socket shell 16, is of the same construction as that herein described. In this form of the invention, however, provision is made for reinforcing the shell bottom 18. For this purpose there is provided a U-shaped plate 70 having a 35 relatively wide connecting portion 72 and spaced portions 74. Said portions 72 and 74 lie against the bottom 18 of the shell, being clamped between the latter and the bottom 20 of the housing recess 14 by center contact 26 and insulation disk 36. Edge 76 of plate 70 between portions 74 terminates at the edge 54 of shell opening 22 in position to lie close to or to be engaged by end portion 52 of clamping member 45.

40 Thus it is seen that the constructions herein shown or described are well adapted to accomplish the several objects of the present invention. It will be understood, however, that the invention may be embodied otherwise than as here shown and that in the forms of the invention herein disclosed, certain changes in the construction and arrangement of parts may be made and will readily occur to skilled artisans, particularly in view of the present disclosure. Therefore we do 45 not wish to be limited precisely to the construction herein shown or described, except as may be required within the scope of the appended claims.

Having thus described our invention, what we 50 claim and desire to secure by Letters Patent is:

1. In an electric socket of the class described, a socket shell having a contact member insulated therefrom and provided with means for connecting a wire to the bottom of the shell externally thereof, said shell having an opening in its bottom, a wire-clamping member positioned for adjustment toward and away from said bottom externally of the shell to releasably connect the wire to the shell bottom, a member passing through said opening and engageable with said clamping member for adjusting the same, the adjusting member being accessible for adjustment, said shell having an opening in its side wall adjacent said bottom in continuation of said bottom opening, and said adjusting member and clamping

member being insertable as a unit in said bottom opening laterally of the side wall of the shell through said opening therein.

2. In an electric socket of the class described, a socket shell having a contact member and provided with means for connecting a wire to the bottom of the shell externally thereof, an insulation member in said shell for insulating said contact member therefrom, said shell having an opening in its bottom, a wire-clamping member positioned for adjustment toward and away from said bottom externally of the shell to releasably connect the wire to the shell bottom, a member passing through said opening and turnably engageable with said clamping member for adjusting the same, the adjusting member being accessible internally of the shell for adjustment, said shell bottom having a second opening for the passage therethrough of said contact member, and said wire-clamping member having a part 10 projecting into said second opening for preventing turning movement of the clamping member when said adjusting member is turned in engagement therewith for clamping the wire in position.

3. In an electric socket of the class described, a socket shell having a contact member insulated therefrom and provided with means for connecting a wire to the bottom of the shell externally thereof, said shell having an opening in its bottom, a wire-clamping member positioned for adjustment toward and away from said bottom externally of the shell to releasably connect the wire to the shell bottom, and a member passing through said opening and engageable with said clamping member for adjusting the same, the adjusting member being accessible internally of the shell for adjustment, said shell having an opening in its side wall adjacent said bottom in continuation of said bottom opening, and said adjusting member and clamping member being insertable as a unit in said bottom opening laterally of the side wall of the shell through said opening therein, said shell bottom having a second opening for the passage therethrough of said contact member, and said wire-clamping member having a part projecting into said second opening for opposing movement of said clamping member through the lateral opening in said shell when the clamping member is in wire-clamping relation.

4. An electric socket of the class described comprising a housing having a recess therein, a socket shell in said recess, said housing having a passage positioned below the bottom of said shell and extending transversely thereof for the insertion of a wire into the housing transversely thereof in juxtaposition to said shell bottom externally thereof, said shell having an opening in its bottom, a wire-clamping member positioned for adjustment toward and away from said bottom externally of the shell to releasably connect the wire to the shell bottom, a member passing through said opening and turnably engageable with said clamping member for adjusting the same, the adjusting member being accessible for adjustment, said bottom of the shell having a second opening and said clamping member having a part projecting into said second opening in the bottom of said shell adjacent the edge of the shell bottom at said second opening to prevent turning movement of the clamping member when said adjusting member is turned for clamping the wire in position.

5. An electric socket of the class described

comprising a housing having a recess therein, a socket shell in said recess, said housing having a lateral passage positioned below the bottom of said shell for the insertion of a wire into the 5 housing transversely thereof in juxtaposition to said shell bottom externally thereof, said shell having an opening in its bottom, a wire-clamping member positioned for adjustment toward and away from said bottom externally of the shell 10 to releasably connect the wire to the shell bottom, a member passing through said opening and turnably engageable with said clamping member for adjusting the same, the adjusting mem-

ber being accessible internally of the shell for adjustment, said clamping member having a part engaging said shell at the edge of said opening for preventing turning of said clamping member when said adjusting member is turned in engagement therewith, said shell bottom having an observation opening in line with said first opening and through which said wire is visible, internally of the shell, when connected to the shell bottom as aforesaid. 10
